UNITED STATES PATENT OFFICE

165,970

KNIFE SHARPENING HOLDER

Daniel D. Duncan, Glendale, Calif.

Application June 5, 1950, Serial No. 10,361

Term of patent 14 years

(Cl. D37—1)

To all whom it may concern:

Be it known that I, Daniel D. Duncan, a citizen of the United States, residing in the city of Glendale, in the county of Los Angeles and State of California, have invented a new, original, and ornamental Design for a Knife Sharpening Holder, of which the following is a specification, reference being had to the accompanying drawing, forming part thereof.

Fig. 1 is a perspective view of a knife sharpening holder showing my new design.

Figs. 2 and 3 are, respectively, front and side elevations of the article on an increased scale.

Fig. 4 is a bottom plan view of the article shown in Fig. 3.

I claim:

The ornamental design for a knife sharpening holder, substantially as shown.

DANIEL D. DUNCAN.
